UNITED STATES PATENT OFFICE.

JOHN R. PERRY, OF CHICAGO, ILLINOIS, ASSIGNOR TO THE PERRY PIPE COMPANY, OF CHICAGO, ILLINOIS, A CORPORATION OF ILLINOIS.

TOBACCO-PIPE.

987,824.

Specification of Letters Patent. Patented Mar. 28, 1911.

Application filed November 15, 1909. Serial No. 528,043.

To all whom it may concern:

Be it known that I, JOHN R. PERRY, a citizen of the United States, residing at Chicago, in the county of Cook and State 5 of Illinois, have invented a new and useful Improvement in Tobacco-Pipes, of which the following is a specification.

My invention relates particularly to means for separating nicotin from tobacco-smoke 10 in pipes, and to preventing saliva from entering the pipe-stem and reaching the bowl of the pipe.

My primary object is to provide an improved construction which will be thoroughly 15 practical to manufacture and of improved operation.

The invention is illustrated in its preferred embodiment in the accompanying drawing, in which—

20 Figure 1 represents a longitudinal sectional view of a pipe constructed in accordance with my invention; Fig. 2, a broken perspective view of the mouth-piece employed; Fig. 3, a perspective view of the 25 combination nicotin-collector and saliva-deflector employed; and Figs. 4 and 5, transverse sectional views taken as indicated at the corresponding line in Fig. 1.

30 In the construction illustrated, A represents a pipe-bowl; B, a stem connected with said bowl; C, a mouth-piece; D, a combined nicotin-collector and saliva-deflector; and E, a tubular nipple, or connecting member.

The stem B, in the construction illustrated, 35 comprises a short section 1 formed integrally with the base of the bowl, and a removable section 2. Obviously, the sections 1 and 2 may be formed integrally with each other if desired. The stem is provided with a 40 straight, smooth bore 3 which extends beneath the chamber 4 of the bowl and communicates therewith through a passage 5 located near the inner end of the bore.

The mouth-piece C is formed with a comparatively 45 large chamber 6 therein, the mouth-piece and chamber being of substantially circular cross-section. The chamber has leading therefrom a smoke-passage 7 which extends through the flattened tip 8 of the mouth-piece. The mouth-piece has an externally-threaded shank 9 which is provided with an angular (square) perforation 10 which communicates with the chamber 6. The member E is of cylindrical form and 50 has its outer end counter-bored and inter-

nally threaded to connect with the reduced threaded portion 9 for the mouth-piece. The outer end of the stem-section 2 is counter-bored, and the inner end of the nipple E is made of reduced diameter, as indicated at 60 11, to be received in said counter-bore, having slip-joint connection therewith.

The device D preferably comprises a rod 12 equipped with a plurality of disks 13 whose lower halves are imperforate and 65 whose upper halves are provided with smoke-passages 14; an extension 15 at the inner end of said rod which projects beneath the chamber of the bowl and is preferably of the same diameter as the disks, 70 said member 15 serving to fill the inner end of the bore 3 and having its upper portion recessed, or cut away, as indicated at 16, to afford a bottom located beneath the passage 5; a shank 17 having a cylindrical portion 75 18 received in the bore of the nipple E and an angular portion 19 received in the squared opening 10 of the mouth-piece; and a saliva separator, or deflector, 20 projecting from the upper portion of the outer end of the portion 19 of the shank 17 into the chamber 6 of the mouth-piece. The portion 18 of the stem 17 is of circular cross-section and of 80 the same diameter as the disks 13. Said portion 18 of said stem projects past the inner end of the nipple E and fits snugly within the outer end of the bore 3. A smoke-passage, or groove, 21 extends longitudinally 85 through the upper portion of the shank 17 and saliva-deflector 20, the outer end of said 90 passage lying adjacent to the upper wall of the mouth-piece. At the base of the squared opening 10 of the mouth-piece is an internal shoulder 22 adapted to abut against the calendar 23 of the squared portion 19 95 of the stem of the device D.

It will be understood from the foregoing description that in screwing the nipple and mouth-piece together the stem of the device D will be securely clamped, or held, and, 100 moreover, rotation of the device D with relation to the mouth-piece will be prevented, by reason of the angular socket of the mouth-piece and the angular portion 19 of the stem which is received therein. When it 105 is desired to cleanse the pipe, the device B may be withdrawn from the stem of the pipe through the medium of the mouth-piece, and may be held by means of the mouth-piece while the rod 12, disks 13 and exten- 110

sion 15 are cleansed, as by circular wiping action. If desired, the mouth-piece and nipple may be disconnected from each other, to enable the shank-portion to be cleansed. It will be observed that the nipple E is of suitable size to permit it to be slipped over the disks 13 and extension 15 in assembling or disconnecting the parts.

In the use of the pipe a substantially straight draw for the smoke through the upper portion of the bore 3, the nipple E and mouth-piece is secured, while the spaces between the imperforate lower portions of the several disks 13 serve as traps for the nicotine and oils of the tobacco which are carried by the smoke and deposited as the smoke passes through the pipe. The improved construction enables an entirely satisfactory draft to be secured, without interfering with the desired object of separating the nicotine and oils of the tobacco. Any saliva which may enter the mouth-piece will be trapped and cannot reach the bore of the stem and the bowl of the pipe. The smoke is cooled in passing through the device D, which is of metal.

The foregoing detailed description has been given for clearness of understanding only. Hence, no undue limitation is to be understood therefrom, but the claims are to be considered as broadly as permissible in view of the prior art.

What I regard as new, and desire to secure by Letters Patent, is—

35 1. A pipe comprising a bowl, a stem formed with a straight, smooth bore therein, a mouth-piece having a chamber with an angular socket at its inner end, a tubular nipple connecting said stem and mouth-piece, 40 and a combination nicotin-collector and saliva-deflector comprising a rod equipped with disks contacting with the walls of said bore, said disks being imperforate throughout substantially their lower halves and having smoke-passages through their upper portions, and a shank extending through said nipple and having an angular portion received in said socket, said shank carrying a saliva-deflector located in the upper portion 50 of the chamber of said mouth-piece, the upper portion of said shank and saliva-deflector having a smoke-passage therethrough.

2. In a device of the character set forth, the combination of a bowl equipped with a stem formed with a straight, smooth bore therein, a mouth-piece having a chamber

therein terminating at its inner end in an angular socket, the inner end of said mouth-piece being externally threaded, a nipple having a counter-bored outer end internally threaded to connect with said mouth-piece and having slip-joint connection with said pipe-stem, and a nicotin-collector equipped with disks contacting with the walls of said bore, said nicotin-collector having a shank 65 comprising a cylindrical section extending through said nipple and an angular section received in the socket of said mouth-piece, said stem having a smoke-passage through its upper portion, for the purpose set forth. 70

3. In a pipe the combination of a bowl equipped with a stem provided with a straight, smooth bore which extends beneath the chamber of the bowl and communicates with said chamber through a passage 75 a short distance from the inner end of the bore, a mouth-piece, a nipple connecting said stem and mouth-piece, a nicotin-collector comprising a rod equipped with disks contacting with the walls of said bore, the lower halves of said disks being imperforate and the upper halves thereof having smoke-passages therethrough, an extension at the inner end of said rod fitting the inner end of said bore and having a cut-away portion at its 80 upper side to afford a bottom for the passage leading from the chamber of the bowl, a shank extending from the outer end of said rod through said nipple and having a smoke-passage in its upper portion, and a saliva-deflector carried by said shank and located in the upper portion of the chamber of said mouth-piece. 85

4. In a device of the character set forth, the combination of a stem provided with a straight smooth bore, a mouth-piece removably connected with said stem, and a nicotin-collector comprising a rod having a shank connected with said mouth-piece, said rod equipped with disks contacting directly with the walls of said bore, said disks being imperforate throughout substantially their lower halves and having smoke-passages through their upper halves, whereby the nicotine and oils may be trapped by the lower portions of said disks and drawn from said bore in the withdrawal of the nicotin-collector, as set forth. 100 105
